HAIR DRIER

Harry A. Lockwood, Bridgeport, Conn.

Application July 29, 1952, Serial No. 301,488

9 Claims. (Cl. 219—39)

1

This invention relates generally to drying apparatus and more particularly to a portable drier such as a hair drier and its supporting stand.

Driers of this general type are known in the art and are usually characterized by a number of inherent disadvantages. Among these are an unnecessary bulk and weight, a highly excessive level of noise in operation, and the discharge of a small stream of air at a high temperature and velocity which, in addition to increasing the noise level, severely increases the danger of the user receiving a burn from the air stream. The driers heretofore available have also had an unnecessarily complicated structure resulting in high first cost and difficulty in maintenance and the replacement of worn parts.

Accordingly, the chief object of the present invention is to provide an improved drier structure which will obviate the above-mentioned undesirable characteristics of known driers.

Another important object of the present invention is to provide an improved portable hair drier including a novel casing which enables the ready assembly of the various parts which cooperate with each other and the casing to maintain their relative operating positions.

A further important object of the invention is to provide an improved portable hair drier which is light in weight and balanced with respect to its supporting handle and stand.

A still further important object of the invention is to provide an improved portable drier having a carrying handle and cooperating stand which enable the heated air from the drier to be manually directed or the drier to be placed on a supporting table, etc., in any of a number of adjusted positions to properly direct the flow of air from the drier nozzle.

Another object of the invention is to provide an improved portable drier embodying operating controls which enable the fan motor to be operated with or without the heating coil.

Other objects and advantages of the invention will become apparent during the course of the following description.

In its broadest aspects, the invention contemplates an improved drier in which a large volume of air is substantially noiselessly discharged at low velocity from a two part plastic case held together by a single screw and so formed as to enable the various parts to cooperate in aligning and maintaining themselves in operative position.

In the drawings I have shown one embodiment of the invention. In this showing:

Figure 1 is a side elevational view of the drier

2

and its supporting stand comprising the present invention;

Figure 2 is a vertical transverse sectional view of the drier taken on the line 2—2 of Figure 1;

Figure 3 is a perspective view of a detail of the case aligning means;

Figure 4 is a vertical longitudinal sectional view of the drier taken on the line 4—4 of Figure 2;

Figure 5 is a perspective view of the heating element; and

Figure 6 is a vertical sectional view of the drier stand.

Referring to the drawings, numeral 10 designates the drier as a whole which for purposes of illustration is shown as the hair drier type and comprises essentially a fan F driven by a relatively low speed electric motor M, a heating unit H, a handle 11 including a switch S, a supporting stand 12 and an electric cord C passing through the stand and connecting the drier motor and heating unit with a suitable source of power.

The drier casing and stand is preferably formed of molded or die cast plastic material of suitable strength for the purpose in question such as polystyrene, phenol-formaldehyde, etc. The generally spherical casing 10 and handle 11 is divided along a substantially central line 13 into an air inlet portion 14 and an air outlet portion 15 and their mating edges are provided with an interfitting annular flange 16 and groove 17 to properly align the hemispherical portions during assembly of the drier.

The casing half 14 is provided with an air inlet port 20 which is provided with a decorative and protective grill work 21 and its handle portion includes an apertured screw-receiving boss 22, the outer portion of the aperture being countersunk for the reception of a screw head. A similar boss 23 having an inwardly opening threaded aperture is provided in the mating handle portion and it will be noted that the sections 14 and 15 of the plastic casing 10 are aligned by the flange 16 and groove 17 while being held together by the single screw 24 through the handle bosses 22 and 23.

The outlet or nozzle half 15 of the casing 10 (Figure 4) is provided with an air discharge port 25 which is diametrically bridged by the web 26 of a generally U-shaped, vertically disposed rib 27 formed integrally with the inner side of the casing. The inner faces of the legs of the rib 27 and the web 26 are provided with a pair of spaced, inwardly projecting flanges which form a guiding and restraining track 30 for the reception and mounting of the heating element H.

The heating element H (Figure 5) is preferably formed of a pair of reversely slotted, interfitting ceramic elements 31 and 32 disposed and held by the engagement of the sides of the slot of one with the surface of the other at right angles to each other and having a heating coil 33 wound about their edges. The edges may be notched to retain the coil turns in position. The element 31 is provided with an arcuate notch 34 in one of its ends for a purpose to be described and with a pair of radially outwardly projecting lugs 35 which support the heating element H in the legs of the track 30. It will be noted that the opposite end of the element 31 projects beyond the same end of the element 32 and engages the web of the track 30 when in operative position. If desired, the ceramic heating elements 31 and 32 may be integral so as to be a one-piece support for the heating coil 33.

The motor M is mounted in vertical position against the ends of the legs of the U-shaped rib 27 by the screws 29 and rotatably mounts the fan F on its horizontal shaft 36. The motor hub portion 37 fits in the arcuate notch 34 of the heating element 31 to clamp it firmly in the track 30 of the casing portion 15.

To further facilitate the assembly of the hemispherical casing halves 14 and 15 and retain them in assembled relationship, an apertured aligning and retaining clip 40 (Figure 3) is mounted against the motor M behind the head of the upper screw 29. The clip is formed with a pair of relatively angularly disposed wings 41 which taper to form a positioning space 42 for the reception of an aligning rib 43 formed longitudinally on the upper inner surface of the casing half 14. Thus, when the casing halves are brought together during assembly, the clip 40 and the rib 43 cooperate to accurately align the casing halves, and the edges of the wings which define the space 42 engage the sides of the rib to frictionally hold the halves together.

It will be noted that in the drier structure described, the motor M is mounted substantially at the midpoint of the casing 10 with the fan F and heating element H on opposite sides thereof. This arrangement ensures proper cooling of the motor M and a proper balance of the drier 10 about its handle 11 resulting in more convenient handling thereof and also enables the drier to maintain any adjusted position when supported by the stand 12 as shown in Figure 1.

As seen in Figure 2, the handle portion 11 of the casing half 15 has formed therein a pair of spaced, centrally located and vertically extending ribs 44 which form a guideway or track for the sliding electrical contacts 45 and 46 of the switch S. The contacts are fixed to and actuated by a knob 47 which is slidable in and projects through a slot 50 formed in the handle 11.

The plurality of vertically spaced horizontal ribs 51 connect the ribs 44 with the inner sides of the handle 11 and act as insulators for fixed contact plates 52, 53, and 54 which also close the guideway formed by the ribs 44 and confine the sliding contacts 45 and 46 therein. The contact plates and their electrical connections are attached to bosses formed in the handle 11 by screws 61. The contacts 45 and 46 are of a resilient electrically conducting material and are held in a compressed condition by contact plates 52, 53, and 54 to insure good electrical contact and hold the switch 47 firmly against the inner wall of the handle 11. An electrical conduit enters the lower end of the handle 11 through an

aperture 55 and connections are made with the contact plates 52, 53, and 54 and with the motor M and the heating element H.

Operation of the drier 10 is readily controlled by the switch knob 47. As seen in Figure 4, the knob is in the "off" position and all of the sliding contacts engage the contact plate 52. When the knob is moved to a position intermediate of the slot 50, the contact 46 engages the contact plate 53 to energize the circuit of the motor M. When the switch knob 47 is moved to the upper end of the slot 50, the contact 46 engages the contact plate 54 to energize the heating element H while the upper end of the double contact 45 engages the plate 53 to also keep the fan motor circuit closed.

The combination of the propeller type fan F, the large inlet port 20, and the converging walls of the casing half 15 to the outlet port 25 produces a large volume of air discharging from the drier at a relatively low velocity. Because of this condition, the air stream remains more homogeneous than is a higher velocity air stream of small cross section and maintains a more constant temperature throughout a greater distance from the outlet 25. A higher velocity stream involves reduced pressure immediately adjacent to the air stream thereby causing ambient air to be mixed with the heated air which results in a more rapid reduction to temperature as the mass progresses. With the drier comprising the present invention, a lower outlet temperature will equal at a distance of one foot the temperature obtained by the high velocity type. The drier 10 may be placed very close to the user's head without danger of burns. In this manner, the drier acts on a large area of the head to dry the hair rapidly and safely.

The stand 12 comprises an open tubular base 63, the axis of which is inclined at an angle with respect to the vertical of 10 or more degrees. The base is provided with a plurality of angularly spaced legs 56 projecting radially therefrom and terminating in downwardly turned feet 57 which space the bottom of the base from the supporting table, etc. The legs are provided with lateral down turned flanges 60 which are notched intermediate the legs as at 59 to ensure adequate clearance for the electrical conduit C which passes up through the base 12 into the drier handle 11.

The lower portion of the inner wall of the base 63 has a plurality of angularly spaced radially projecting lugs 62 formed integral therewith and having upwardly and outwardly inclined faces which cooperate to form a tapered supporting socket for the lower end of the handle 11 (Figures 1 and 6). When the handle 11 rests in the socket, the upper peripheral edge of the tubular base 63 will engage the periphery of the handle 11 intermediate its length due to the taper of the handle.

In use, the drier may be manually held with or without the stand while the air blast is directed on the object to be dried. If the handle 11 alone is picked up, the electrical conduit C will be readily drawn through the tubular base 63 while the stand 12 remains in place. However, the handle 11 and the base 12 may be simultaneously picked up and easily held during the desired manipulation of the drier.

As shown in Figure 1, the drier and stand may be placed on a support such as a table, etc. with the air blast directed on the object to be dried. A ready adjustment of the direction of the air

blast is effected by turning the handle 11 and the base 12 with respect to each other due to the angular inclination of the tubular base 63.

The assembly of the drier and stand is readily and easily accomplished. With the various parts at hand or during the process of the casing halves 14 and 15 down an assembly line, the heating element H is first inserted in the track 30 in the hemispherical half 15, the circuit wires being first connected to the element H. The motor M, fan F and the aligning and retaining clip 40 are assembled as a unit and clamped to the ribs 27 by the screws 29 to complete the assembly in the hemispherical portion of the casing section 15.

The sliding contacts 45 and 46 are now placed in the track formed by the ribs 44 with the switch control knob 47 projecting through the slot 50. The contact plates 52, 53 and 54 are now positioned between the horizontal insulating ribs 51 and, after the circuit wires to the motor M and the heater element H are connected, screwed to the handle. The electrical conduit C which need not be fed up through the base 12 as the plug will pass therethrough is now connected to the above circuit wires.

The two halves 14 and 15 of the casing 10 are now aligned and partly held together by the rib 43 and the aligning and retaining clip 40 and connected together in rigid assembly by the single screw 24 in the handle 11. It will be readily apparent that the drier 10 may be as readily disassembled for repair or inspection as required.

It will now be seen that the drier and stand comprising the present invention provide a light weight, balanced device which may be readily manufactured, assembled and repaired, is very efficient and quiet in use whether manually held or not, and which will deliver a large volume of air at a relatively low velocity, heated or not as desired. The large volume, low temperature and velocity stream of air discharged from the drier makes it unnecessary to hold the fan at arms length and thereby greatly reduces fatigue when manually supported. Moreover, fatigue to the user is further reduced by the combination of the propeller type fan which practically completely eliminates any noise of operation.

It is to be understood that the form of the invention herewith shown and described is to be taken as a preferred example of the same and that various changes in the shape, size and arrangement of parts may be resorted to without departure from the spirit of the invention or the scope of the subjoined claims.

I claim:

1. A portable drier comprising a casing having a supporting handle depending therefrom, air inlet and outlet ports formed in said casing, a heating element mounted in said casing, and a fan including a motor mounted in said casing over said handle to balance the casing with respect to the handle, said heating element being clamped in said casing against said outlet port by said motor.

2. A portable drier comprising a casing having a supporting handle depending therefrom, air inlet and outlet ports formed in said casing, a heating element mounted in said casing, a fan including a motor mounted in said casing over said handle to balance the casing with respect to the handle, and supporting means for said handle, said supporting means comprising a tubular base angularly disposed with respect to the vertical.

3. A casing for a drier including a heating element, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, and means for clamping the heating element in said tracks against the web.

4. A casing for a drier including a heating element, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, and means for clamping the heating element in said tracks against the web, said casing and said handle being separable along a line substantially at their common midpoint.

5. A casing for a drier including a heating element, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, means for clamping the heating element in said tracks against the web, and means for supporting said casing and said handle with the longitudinal axis of the casing in a horizontal position.

6. A casing for a drier including a heating element, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, means for clamping the heating element in said tracks against the web, and means for supporting said casing and said handle in an inclined position.

7. A casing for a drier including a heating element, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, means for clamping the heating element in said tracks against the web, and means for supporting said casing and said handle with the longitudinal axis of the casing in a horizontal position, said supporting means comprising a tubular base angularly disposed with respect to the vertical.

8. A casing for a drier including a heating element, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, means for clamping the heating element in said tracks against the web, and means for supporting said casing and said handle in an inclined position, said supporting means comprising a tubular base angularly disposed with respect to the vertical.

9. A casing for a drier including a heating ele-

ment, a fan and a motor for driving the fan comprising a generally spherical casing having inlet and outlet ports and a handle depending centrally therefrom, a U-shaped rib in said casing having its web spanning one of said ports, flanges on the inner faces of said rib to slidably receive and restrain the heating element, means for clamping the heating element in said tracks against the web, and means for supporting said casing and said handle with the longitudinal axis of the casing in a horizontal posi-

tion, said supporting means and said handle being relatively rotatable to effect an angular position change with respect to said axis.
